UNITED STATES PATENT OFFICE

GEORGE W. HOOVER, OF ELWYN, PENNSYLVANIA

DESIGN FOR A NAPKIN RING

Application filed May 27, 1930. Serial No. 35,788. Term of patent 14 years.

To all whom it may concern:

Be it known that I, GEORGE W. HOOVER, a citizen of the United States, resident at Elwyn, in the county of Delaware and State of Pennsylvania, have invented a new, original, and ornamental Design for Napkin Ring, of which the following is a specification, reference being had to the accompanying drawing, forming part thereof.

I claim:

The ornamental design for a napkin ring as shown.

GEORGE W. HOOVER.
